Section 1, Public Law 690, August 8, 1946
Patent expires March 19, 1963

5 Claims. (Cl. 202—42)

1

This invention relates to the treatment by distillation of complex mixtures and has for its chief object the provision of an improved method of and means for separating by distillation the components of azeotropic and like mixtures difficultly resolvable by simple distillation into their components.

It is known, for example, that acetone and methyl alcohol mixed in certain proportions give a constant boiling point mixture and that such a mixture is not resolvable into its components by simple distillation as an azeotrope distils over unchanged.

It is also known that paraffinoid and aromatic hydrocarbons of closely related boiling points give mixtures which are not readily resolvable by simple distillation so that even under conditions of high reflux the distillate consists of a mixture of paraffinoid and aromatic hydrocarbons. This may be due to the tendency of aromatic hydrocarbons to form azeotropes with hydrocarbons of other series.

It is also known that difficulties are experienced in separating acetone from methyl alcohol in the products obtained by the carbonisation of wood, sawdust and the like and in separating the aromatic hydrocarbons from the paraffinoid stocks derived, for example, from petroleum, the carbonisation of coal and the like.

According to the present invention an acetone-methanol mixture is distilled in the presence of a paraffinoid-aromatic hydrocarbon mixture so that two components, one from each of the mixtures, are removed in the top product whilst the remaining two components are removed in the bottom product.

If it is desired to separate acetone from admixture with methyl alcohol, the mixture may be fed to a distillation column together with a mixture of paraffinoid and aromatic hydrocarbons and heat is applied in the usual manner. At comparatively low reflux ratios, a distillate is obtained containing substantially all the acetone and paraffinoid hydrocarbons whilst substantially all the methyl alcohol and aromatic hydrocarbons are found in the lower part of the column. The acetone may then be removed from admixture with paraffinoid hydrocarbons by washing, for example, with water and decantation followed by concentration in a rectification column or other known means. The methyl alcohol may be removed by similar treatment of the effluent mixture of methyl alcohol with aromatic hydrocarbons leaving the base of the column by washing, for instance, with water and decantation fol-

lowed by concentration in a rectification column or other known means.

Conversely, if it is desired to separate paraffinoid hydrocarbons from admixture with aromatic hydrocarbons, the mixture is fed to a distillation column together with a mixture of acetone and methyl alcohol and heat is applied in the usual manner. At comparatively low reflux ratios such as 1 to 1 to 3 to 1, a distillate is obtained containing substantially all the paraffinoid hydrocarbons and acetone. The paraffinoids may be recovered by washing with water or other preferential solute for acetone and decanting off the hydrocarbon layer and freeing same from any acetone and/or water remaining in the hydrocarbon layer by running same through a heated stripping column where the acetone and/or water are removed as top products.

20 Thus, means are provided for recovering methyl alcohol in the first case and aromatic hydrocarbons in the second case. As both of these will be found in the lower part of the distillation column whence they can be removed and recovered as commercial products by known means.

25 For many reasons, it is convenient to carry out this invention in the presence of water. It is not necessary to use anhydrous entraining mixtures and satisfactory results have been obtained under continuous distillation conditions with a mixture of acetone and methyl alcohol with more than its own volume of water.

30 The invention is carried out in a continuous type of distillation apparatus. It has been found that in a continuous type of distillation apparatus containing one column it is possible to perform both the separation of components before described together with the regeneration of the acetone from the aqueous solution resulting from water washing the distillate, thus obviating the need for a separate acetone recovery column in cases where the products to be removed from the system are hydrocarbons and the need for supplying additional water to resolve the bottom product into its components as substantially all the water fed to the column passes to the lower part thereof together with the methyl alcohol and aromatic hydrocarbons.

35 It has been found in practice that it is sometimes possible when using an aqueous solution of acetone and methyl alcohol as the entraining agent to form a zone in the distillation column in which substantially all the methyl alcohol is held, i. e. it does not appear in either the 40 distillate or effluent in substantial amounts.

Therefore, under such conditions, the quantity of methyl alcohol in the circulating entrainer solution will be decreased. When the column is working in this manner, the quantity of methyl alcohol passing to the bottom decanter is very small, e. g. 0.1 to 0.5 per cent calculated on the water leaving the base of the column.

Similarly, it is advantageous when separating a wood spirit consisting essentially of acetone and methyl alcohol to feed this to the column in the form of an aqueous solution. In this case it may be found preferable to return both the paraffinoid and aromatic hydrocarbons back to the column immediately after decantation of the respective hydrocarbon layers thus using the process as a means of continuously producing acetone and methyl alcohol and using a continuous recirculation of a limited quantity of mixed hydrocarbons to effect the separation.

Conversely, it is possible continuously to separate a mixture of aromatic and non-aromatic hydrocarbons by using a limited quantity of a mixture of acetone and methyl alcohol which is recirculated preferably in the form of an aqueous solution.

As an example, a mixed hydrocarbon fraction derived from the carbonization of coal of S. G. 0.844 and of approximate composition:

	Percent by volume
Non-aromatics	25
Aromatics	75

and distilling 5% @ 109.8 deg. C. and 95% @ 114.4 deg. C. may be used, there being mixed with one volume of this 5.2 volumes of an aqueous solution containing 47.5% of acetone and 2.5% of methyl alcohol by volume.

This mixture is fed to a continuous type of column having 48 plates and is distilled under a reflux ratio of 1.5 to 1, with a temperature of about 57° C. at the top of the column, a temperature of 70/75° C. at a position about seven plates from the bottom of the column and a temperature of 90/95° C. at the base of the column when it will be found that 2.7 volumes of distillate are obtained and this will contain about 1% of water, the remainder being hydrocarbons and acetone but no methyl alcohol.

This distillate on washing with an equal quantity of water in a counter current scrubber yields 7.7% of its volume (0.21 volume of the hydrocarbon feed) as a decanted hydrocarbon layer of S. G. 0.746 containing 93.5% of non-aromatic and 6.4% of aromatic hydrocarbons together with a trace of acetone.

The product from the bottom of the column is found to amount to 3.7 volumes containing all the methyl alcohol in the feed with the remainder of the hydrocarbons and water with only a trace of acetone.

This product separates into two layers when decanted. The top layer which consists of hydrocarbons amounting to 0.79 volume of the hydrocarbon feed has a S. G. of 0.8702 and contains 0.1% of methyl alcohol water mixture in solution. The aqueous layer contains about 5% by volume of methyl alcohol and 0.2% only of acetone.

This aqueous solution is returned as wash water to the counter current scrubber into which the distillate is led and the resultant aqueous layer from this scrubber will contain substantially all the acetone and methyl alcohol in the system diluted to about 50% by volume with water and is recirculated continuously with fresh hydrocarbons as feed to the column.

As a further example, it may be mentioned that a mixed hydrocarbon fraction derived from low gravity crude benzole of S. G. 0.837 and of approximate composition: paraffinoid hydrocarbons—30% by volume and aromatic hydrocarbons—70% by volume, and distilling an Engler distillation 5% to 95% within 5° C. with not less than 90% at 112° C., may be used, there being mixed with one volume of this hydrocarbon mixture 6.49 volumes of an aqueous solution containing 54.9% of acetone and 2.0% of methyl alcohol. The mixture is fed to a continuous type of column having 45 plates and is distilled under a reflux ratio of the order of 2.5 to 1, the temperature at the top of the column being about 57° C., the temperature at a zone 7 plates from the base of the column being 72/75° C. and the temperature at the base of the column being 87/92° C. In this way, it has been found that 3.9 volumes of distillate are obtained which has the following analysis:

Dissolved hydrocarbons (S. G.	
0.758)	7.3% by volume
Methyl alcohol	Less than .01%
Water	1.4% by volume
Acetone	Remainder

Such distillate on washing, for example, in a countercurrent scrubber with the aqueous solution decanted from the effluent at the base of the column (3.1 volumes containing 4% of methyl alcohol) has been found to yield 7.3% of its volume (0.28 volume of the hydrocarbon feed) as a decanted hydrocarbon layer of S. G. 0.758 containing about 92% of paraffinoid and 8% of aromatic hydrocarbons with only a trace of acetone. The effluent from the bottom of the column amounts to some 3.8 volumes containing all the methyl alcohol in the feed with the remainder of the hydrocarbons and water with only a trace of acetone. This effluent separates into two layers when decanted, the lower aqueous layer amounting to some 3.1 volumes having the following analysis:

	Per cent by volume
Methyl alcohol	4
Acetone	0.19
Water, remainder	

Such lower layer is removed and recirculated, for example, to the counter-current scrubber wherein the distillate is washed. The top layer decanted from the effluent consists of hydrocarbons amounting to 0.72 volume of the hydrocarbon feed, has a density of 0.8680 and contains about 94% aromatics with a small quantity (less than 0.1%) of methyl alcohol in solution and is removed continuously. When refined in known manner, for example, by washing with strong sulphuric acid and redistilling, this fraction yields substantially pure toluene of S. G. 0.8698 with a boiling range (5/97%) of 0.19° C. in a yield equivalent to about 95% of the toluene present in the original feed.

It is to be understood that unsaturated bodies and/or organic sulphur compounds such as those usually present in commercial fractions prepared from coal carbonisation or petroleum products may also be present in the original feed. The majority of the unsaturated bodies will be found in the distillate whereas the sulphur compounds will normally be found in the bottom product. For example, where the feed contains unsaturated hydrocarbons giving a total bromine absorption of 18.8 grams per 100 ml. and organic sulphur compounds equivalent to 0.13% of the

total sulphur by weight, the hydrocarbons separated from the distillate may have a bromine absorption of 56.5 grams per 100 ml. and a total sulphur content of 0.02% while the effluent hydrocarbon product amounting to 70.7% by volume of the feed may have a bromine absorption of 3.9 grams per 100 ml. and a total sulphur content of 0.17% by weight. Thus, the distillate contains 85% of the total unsaturated hydrocarbons while the effluent product contains 96% of the sulphur compounds present in the feed.

Alternatively, there may be used as a feed a fraction containing paraffinoid and aromatic hydrocarbons derived from petroleum. Such fractions are often prepared by thermal and/or catalytic reforming processes or by straight run distillation of aromatic containing crudes. For example, a concentrated cut from reformed naphtha stocks prepared by the Polyform and Houdry processes may have a S. G. of 0.7695 and contain 17.5% of aromatics by volume together with a considerable proportion of methyl cyclohexane and distil 5% at 102.1 deg. C. and 95% at 111.8 deg. C. Such a fraction whilst not being readily resolvable by simple distillation even at high reflux ratio is separable into its main components by distillation if this takes place in the presence of a mixture of acetone with methyl alcohol in the manner indicated above.

As a further example, a thermally reformed naphtha from a Mid-Continent petroleum crude may be distilled to yield a concentrate fraction of S. G. 0.7794 with true boiling point curve exclusively between 90° and 118° C. and distilling on Engler test 5% at 104.6° C., 50% at 105.8° C. and 95% at 110.2° C., and of approximate composition: paraffinoid hydrocarbons 78% by volume and aromatic hydrocarbons 22% by volume with unsaturated hydrocarbons giving a bromine absorption of 43.4 grams per 100 ml. One volume of this hydrocarbon mixture may be mixed with 7.15 volumes of an aqueous solution containing 46.4% of acetone and 3.1% of methyl alcohol and fed to a continuous type of column 29 mm. in diameter and packed with $\frac{1}{4}$ inch Raschig rings for a total packed height of 8 ft. 6 inches. The mixture is then distilled under a reflux ratio of about 1 to 1 with sufficient input of heat to maintain the temperatures at the top of the column at 57° C., at a point in the column immediately above 1 ft. 8 inches of packing measured from the base of the packed column at 74° C. and in the heating section at the base of the column at 94° C. In this way, it has been found that 4.17 volumes of distillate are obtained which has the following analysis:

Percent by volume	
Dissolved hydrocarbons	18.5
Water	1.8
Acetone, remainder.	

Such distillate on washing twice with an equal volume of water has been found to yield 18.5% of its volume (0.77 volume of the hydrocarbon feed) as a decanted hydrocarbon layer of S. G. 0.7530 containing about 98.4% of paraffinoid and 1.6% of aromatic hydrocarbons with only a trace of acetone and having a bromine absorption of 52.5 grms. per 100 ml.

The effluent from the bottom of the column amounts to some 4.24 volumes containing all the methyl alcohol in the feed with the remainder of the hydrocarbons and water with only a trace of acetone. This effluent separates into two layers when decanted, the lower aqueous layer amount-

ing to some 4.01 volumes having the following analysis:

	Percent by volume
Methyl alcohol	4.9
Acetone	0.12
Water, remainder.	

The top layer decanted from the effluent amounting to 0.23 volume of the hydrocarbon feed, has a S. G. of 0.869 and contains 90.1% by volume of aromatics with a small quantity (less than 0.1%) of methyl alcohol in solution. When refined in known manner, for example, by washing with strong sulphuric acid and redistilling, this fraction yields substantially pure toluene of S. G. 0.871 in a yield equivalent to about 91.5% of the toluene present in the original feed.

In carrying the invention into practice, any suitable form of continuous distillation unit may be used and distillation may be carried out at pressures below or above atmospheric. The accompanying drawing shows diagrammatically and by way of example one convenient form of apparatus which is suitable for the purpose in view and which includes a fractionation column 3 provided at a suitable point intermediate between the top and the bottom with a feed pipe 1 having a control valve 2. The column is equipped with the usual ancillary apparatus including means such as a steam heated calandria 4 for producing vapour by heat at the base and means such as a water cooled condenser 5 for condensing the vapours leaving the top of the column.

In operation, a mixture of paraffinoid and aromatic hydrocarbons obtained, for example, from the carbonisation of Scottish coal in vertical retorts and having an Engler boiling range (5 to 95%) of 5° C. with 90% distilling at about 112° C., is fed to the column through the pipe line 1 and, at the same time, a solution of acetone and methyl alcohol in water which may contain a trace of dissolved hydrocarbons is fed from a balance tank 6 through a pipe line 7 and control valve 8 to a suitable point in the column. Vapours consisting essentially of non-aromatic hydrocarbons and acetone leave the top of the column 3 through the pipe line 9, are condensed in the condenser 5 and split into two streams by a reflux divider 10 or a similar known means for maintaining a constant reflux ratio, one stream being returned to the top of the column as reflux through a pipe line 11. The other stream is permitted to flow as product through a pipe line 12 to the base of the scrubbing section of a countercurrent scrubber-decanter 13 where it meets in countercurrent flow a stream of a dilute solution of methyl alcohol in water which is fed from a balance tank 14 through a pipe line 15 and a control valve 16 to the top of the scrubbing section of the scrubber-decanter. Here, the mixture separates into two layers, the lighter layer consisting essentially of paraffinoid hydrocarbons rising to the top of the scrubber-decanter and overflowing through the pipe line 17 to storage tank 18. The heavier layer consisting of a solution of acetone and methyl alcohol in water, together with possibly a small trace of dissolved hydrocarbons, is removed continuously from the bottom of the scrubber-decanter by suitable means and is returned through the pipe line 19 to the balance tank 6 and thence recirculated back as part of the feed to the column 3.

At the same time, a mixture of aromatic hydrocarbons, methyl alcohol and water substantially free from acetone overflows or is continuously removed by suitable means from the base of the

column 3 and is fed through the pipe line 28 to a decanter 21. The upper layer consisting essentially of aromatic hydrocarbons decants and overflows through a pipe line 22 to a storage tank 23 and the lower layer consisting of a dilute solution of methyl alcohol in water is removed continuously by known means from the base of the decanter 21 and is fed through a pipe line 24 to the balance tank 14 and is then used as scrubbing agent in the scrubber-decanter 13, as before described.

It is to be understood that by the expression "paraffinoid hydrocarbons" is meant saturated hydrocarbons (straight chain, branch chain and cyclic) and/or unsaturated hydrocarbons (straight chain, branch chain and cyclic), such unsaturated hydrocarbons being characterised in that they have one or more olefinic double bonds in their structure, and/or other types of hydrocarbons excluding only hydrocarbons having one or more benzene rings in their structure which are termed aromatic hydrocarbons. It is also understood that the methyl alcohol acetone mixture used will always contain a trace or more of water.

We claim:

1. A distillation treatment of complex mixtures of mutually soluble liquids inseparable or separable only with difficulty by simple distillation, comprising continuously distilling a mixed hydrocarbon fraction containing approximately 25% by volume of non-aromatics and 75% by volume of aromatics and continuously distilling between 109.8 and 114.4° C. in a distillation column with an aqueous solution containing approximately 47.5% of acetone and 2.5% of methyl alcohol by volume, under a reflux ratio of the order of 1.5 to 1 with a temperature of about 57° C. at the top of the column, an intermediate temperature of 70 to 75° C. and 90° to 95° C. at the bottom of the column, so that the acetone from the mixture is continuously removed in the top product with the paraffinoid components while the remaining components are removed in the effluent from the base of the column.

2. A distillation treatment of complex mixtures of mutually soluble liquids inseparable or separable only with difficulty by simple distillation, comprising continuously distilling a mixed hydrocarbon fraction containing approximately 30% by volume of paraffinoid hydrocarbons and 70% by volume of aromatic hydrocarbons and continuously distilling with not less than 90% at about 112° C., in a distillation column with an aqueous solution containing approximately 55% of acetone and 2% of methyl alcohol by volume under a reflux ratio of the order of 2.5 to 1 with a temperature of about 57° C. at the top of the column, an intermediate temperature of about 73° C. about one fifth up the column from the base and a bottom temperature of about 90° C. so that the acetone from the

mixture is continuously removed in the top product with the paraffinoid components while the remaining components are removed in the effluent from the base of the column.

3. A distillation treatment of complex mixtures of mutually soluble liquids inseparable or separable only with difficulty by simple distillation, comprising continuously distilling a mixed hydrocarbon fraction containing about 15% to 25% of aromatic hydrocarbons and 85% to 75% of paraffinoids with a true boiling point of 90° to 118° C. in a distillation column with an aqueous solution containing 40 to 50% of acetone and 1% to 8% of methyl alcohol under a reflux ratio of 0.8 to 2.0 to 1 with a temperature slightly above the boiling point of acetone at the top of the column and a temperature of 93°/95° C. in the heating section of the column so that the acetone from the mixture is continuously removed in the top product with the paraffinoid components while the remaining components are removed in the effluent from the base of the column.

4. A distillation treatment as claimed in claim 3 in which the vapours leaving the top of the column are condensed and divided into two streams by means adapted to maintain a constant reflux ratio, one stream being returned to the top of the column as reflux and the other being subjected to scrubbing in counter-current flow a stream of a dilute solution of methyl alcohol in water.

5. A distillation treatment as claimed in claim 3 in which the effluent leaving the base of the column is separated and the decanted aqueous layer consisting of a dilute solution of methyl alcohol and water is used in a scrubbing operation in counter-current flow with the distillate from the column and after separation of the methyl alcohol the aqueous layer now consisting of acetone, water and some methyl alcohol is fed back to the column as reconstituted entrainer.
